UNITED STATES PATENT OFFICE.

SOLOMON EISENBERG, OF SYRACUSE, NEW YORK.

DESIGN FOR A FINGER RING, BRACELET, OR ARTICLE OF SIMILAR NATURE.

Application filed January 18, 1923. Serial No. 4,927. Term of patent 7 years.

To all whom it may concern:

Be it known that I, SOLOMON EISENBERG, a citizen of the United States, residing at 807 Madison Street, Syracuse, Onondaga County, State of New York, have invented a new, original, and ornamental Design for Finger Ring, Bracelet, or Article of Similar Nature, of which the following is a specification, reference being had to the accompanying drawing, forming part thereof.

The drawing shows a perspective view of a finger ring showing my new design.

What I claim is:

The ornamental design for a finger ring, bracelet, or article of similar nature substantially as shown.

SOLOMON EISENBERG.
